FIG. 1

FIG. 5

FIG. 2

FIG. 6

FIG. 3

FIG. 4

FIGURE 1 is a front perspective view of an elevator car showing my new design;

FIGURE 2 is a sectional perspective view of the interior of the elevator car as viewed from the rear;

FIGURE 3 is a sectional perspective view of the interior of the elevator car as viewed from the front;

FIGURE 4 is an enlarged fragmentary perspective view of the upper left portion of the car as viewed from FIGURE 2;

FIGURE 5 is a cross-sectional view of the car taken along the line 5—5 of FIGURE 2; and

FIGURE 6 is a cross-sectional view thereof taken along the line 6—6 of FIGURE 3.

The side of the car not shown is substantially the same in appearance as the side shown in FIGURE 1 and the top, bottom and rear not shown are substantially plain.

The dominant features of my design reside in the portion shown in full lines and such full lines being characterized by the interior of the car.

I claim:

The ornamental design for an elevator car, substantially as shown and described.
